F. A. BRUCKMAN,
PASTRY MAKING MACHINE,
APPLICATION FILED JUNE 8, 1916.

1,216,275.

Patented Feb. 20, 1917.

UNITED STATES PATENT OFFICE.

FREDERICK A. BRUCKMAN, OF PORTLAND, OREGON.

PAstry-MAKING MACHINE.

1,216,275.

Specification of Letters Patent. Patented Feb. 20, 1917.

Application filed June 8, 1916. Serial No. 102,560.

To all whom it may concern:

Be it known that I, FREDERICK A. BRUCKMAN, residing at Portland, in the county of Multnomah and State of Oregon, have invented certain new and useful Improvements in Pastry-Making Machines, of which the following is a specification.

My invention embodies certain new and useful improvements in the machine disclosed in my Patent #1,071,027, issued August 26, 1913 and my Patent #1,075,625, issued October 14, 1913, and the present invention has for the particular object to provide means for holding the batter tank from lowering until the cores have been removed therefrom and the additional supply of dough can be introduced into the tank from the reservoir.

I have found, in practice, that the added weight due to the displacement of the cores while dipping, will cause a more or less partial lowering of the tank after the tank raising cam, (see Patent #1,075,625) has disengaged the rod or bar 229. This lowering of the tank before the cores are removed from the batter frequently results in the application of an inadequate supply of batter to the cores and when the machine is running rapidly, the supply of batter to the cores is not always uniformly applied. In order therefore to overcome these objections, I have provided the mechanism which constitutes the present invention, for the purpose of holding up the batter tank for a short interval of time after the tank raising cam has disengaged the tank arm, and until the cores have been adequately supplied with batter and sufficient batter has been allowed to flow into the tank from the reservoir valve to approximate the normal amount.

In its more detail nature, the invention includes those novel details of construction, combination and arrangement of parts, all of which will be first fully described, then be specifically pointed out in the appended claims, and illustrated in the accompanying drawings, in which:—

Figure 1 is a vertical section and part elevation of a set of molding devices at the loading or dipping position, the parts being in the position they assume just prior to the dipping operation.

Fig. 2 is a detail elevation showing the position of the dipping arm at the time the cores are to be dipped (the cores being

omitted) and showing the present invention in use for holding the tank.

Fig. 3 is a detail elevation of a portion of the invention showing the cams on the oscillatable shaft.

Fig. 4 is a detail top plan view of the rocking arm and grip fingers, the tank arm being indicated in end view.

In the drawing, in which like numerals indicate like parts in all of the figures, 15 represents the cores which are mounted on the core bar 14 by cap screws 83 and are designed to enter the parison molds 66 during the baking operation.

23 is the frame of the machine on which a suitable bracket is fastened, the bracket having guides 225 for the side arms (not shown, but see 224 in Patent #1,075,625) that guide the frame 223 which is adjustable up and down by the screw 220.

The frame 223 is provided with rocking arms 226 journaled at 227 and 99 in the frame 223, one of the arms 226 being extended at 22 to receive a weight 103 that is adjustably hung on the arm to counter-balance the weight of the batter tank 25 which is set in the frame 100 that is pivoted at 228 to the respective arms 226.

20 is the rock shaft which receives motion from the chain 41 and which is provided with the cam 230 that is designed to cooperatively engage the arm 229 that extends upwardly from the frame 100. The cam 230 when moved to the position shown in Fig. 2 raises the tank 25 to meet the dipping cores by rocking the tank through the medium of the arms 226.

92 is the oscillatable dipping arm which is provided with the elongated lifting finger 93 and is also provided with the pivoted track 243 which tank has a bead 246 to engage the roller 82 on the end of the core bar 14, the finger 93 being adapted to engage the shouldered portion 81 of the end of the core bar 14 in lifting the core bar to extract the cores from the mold 66 and dip them into the tank 25.

231 represents the batter pan rings. All parts shown in the present drawing and numbered below 300 may be of the same general construction, as the correspondingly numbered parts in my Patent #1,075,625, save that the arm 229 is extended upwardly in such way that it can be grasped by the fingers 304 on the rocking arm 303 that is journaled at 301 on a stud secured to the

frame 23. The arm 303 has an extension 302 that co-operates with a second cam 300 on the shaft 20 and is held in engagement with such cam by a retraction spring 305. 5 The operation of the parts mentioned is the same as the corresponding parts shown in my Patent #1,075,625, except that when the parts are positioned as shown in Fig. 2 of the present drawing, the cam 300 will rock 10 the arm 303 to cause the fingers 304 to grip the end of the rod 229 and hold such rod after the cam 230 has disengaged the arm 229 on the return oscillation of the arm 92. The fingers 304 grip the arm 229 until the 15 cam 300 disengages the extension 302 of the arm 303, by which time the cores will have been lifted out of the batter and the supply of fresh batter from the batter valve (not shown in the present drawing) will have 20 been supplied to the tank 25, at which time the fingers 304 will have disengaged the arm 229 and the tank 25 will drop, subject to the counterbalancing weight 103.

In this way, a more even application of 25 the batter to the cores is obtained, and a more uniform product of the machine is produced.

From the foregoing description, taken in 30 connection with the accompanying drawings, it is thought the complete construction, operation and advantages of my invention will be readily understood by those skilled in the art to which the invention relates.

What I claim is:

- 35 1. In a machine of the class described, the combination with the counterbalanced batter receptacle, an oscillatable dipping arm shaft, an arm that extends from the batter receptacle to adjacent to said shaft, and the 40 batter receptacle raising cam on said shaft; of means for holding the batter receptacle raised for a predetermined interval after said cam disengages said arm on its return movement.
- 45 2. In a machine of the class described, the combination with the counterbalanced batter receptacle, an oscillatable dipping arm shaft, an arm that extends from the batter receptacle to adjacent to said shaft and the batter 50 receptacle raising cam on said shaft; of means for holding the batter receptacle raised for a predetermined interval after said cam disengages said arm on its return movement, said last named means comprising 55 a lever having gripping fingers for engaging said batter receptacle moving arm—to hold said receptacle elevated and an auxiliary cam on said rock shaft for actuating said holding lever.
- 60 3. In a machine of the class described, bodily movable molding devices adapted to

be moved from one position to another, said molding devices including molds and cores therefor, a core bar carrying said cores, a dipping tank, means for transferring said 65 cores from the molds into the dipping tank and restoring said cores again to said molds, said means including an oscillatable shaft and a dipping arm, means for raising said dipping tank to meet the cores while being 70 dipped, means for counterbalancing the weight of said tank, and other means for holding said tank raised against the action of said counterbalancing means during a 75 predetermined part of the time of the dipping act.

4. In a machine of the class described, bodily movable molding devices adapted to be moved from one position to another, said molding devices including molds and cores 80 therefor, a core bar carrying said cores, a dipping tank, means for transferring said cores from the molds into the dipping tank and restoring said cores again to said molds, said means including an oscillatable shaft 85 and a dipping arm, means for raising said dipping tank to meet the cores while being dipped, means for counterbalancing the weight of said tank, other means for holding said tank raised against the action of 90 said counterbalancing means during a predetermined part of the time of the dipping act, said last named means comprising a member projecting from the dipping tank, and a gripping device for engaging said 95 member, and means for bringing said gripping device into and out of action.

5. In a machine of the class described, the combination with the counterbalanced dipping tank and the core dipping mechanism 100 which includes the oscillatable shaft and an arm mounted thereon to engage the core carrier, means operated by said oscillatable shaft for raising said dipping tank as said cores are dipped into the same, and other 105 means for holding said tank raised after said oscillatable shaft has discontinued its function of raising said tank, substantially as shown and for the purposes described.

6. In a machine of the class described, the 110 combination with the dipping tank and the counterbalanced frame on which said tank is mounted and the oscillatable dipping shaft; an arm on said tank, a cam on said shaft for engaging said arm to move said tank in one direction, a device for engaging said tank bar to hold said tank at the limit of its movement in one direction and an operating cam on said oscillatable shaft 115 for actuating said holding device.

FREDERICK A. BRUCKMAN.
